UNITED STATES PATENT OFFICE.

HENRY PETERS, OF RAHWAY, NEW JERSEY.

PROCESS OF REPRODUCING PICTURES.

1,143,860.

Specification of Letters Patent. Patented June 22, 1915.

No Drawing.

Application filed December 9, 1913. Serial No. 805,661.

To all whom it may concern:

Be it known that I, HENRY PETERS, a subject of the German Empire, and resident of Rahway, in the county of Union and State 5 of New Jersey, have invented certain new and useful Improvements in Processes of Reproducing Pictures, of which the following is a specification.

My invention relates to certain improvements in the process of making reproductions of pictures and more particularly the reproduction of oil paintings.

The main object of my invention is to more effectively secure a copy which, in 15 appearance, will simulate an original, not only in regard to the colors, lines and shading of the latter, but also in regard to such surface irregularities as the structure of the canvas, the varying thicknesses of paint, 20 brush marks, finger prints, etc.

In carrying out my improved process I first make or secure a photographic reproduction of the painting in its true and natural colors on the surface of a readily em- 25 bossable material, such as paper, and by the use of the ordinary tri-color or four-color printing process. This ordinarily includes the making of separate photographic plates with different color screens interposed and 30 the printing of separate superposed impres-

sions with different colored inks from printing plates made from the corresponding photographic plates. This photographic reproduction in the natural colors may be 35 made by any well-known process now employed, or I may purchase colored prints already made by others. These prints may be the same size as the original painting or may be larger or smaller. I next make an 40 intaglio to be used as a die. This I may do by supporting the painting in a horizontal position with a suitable frame around it and pour on to the painting a solution which will not injure or in any wise effect the 45 structure, color or other characteristics of the painting, but which upon evaporation of the solution will leave a matrix, die or intaglio, the under surface of which will conform in the minutest detail to the sur-

50 face irregularities of the painting. The compound which I preferably employ is made up of ten parts of cellulose acetate, eighty parts of tetrachlorethane, and five parts of dichlorhydrin, the parts being de- 55 termined by weight. The cellulose acetate which is employed is preferably such as is

soluble in acetone. The exact proportions of these ingredients is not essential and other ingredients may be employed as substitutes for those specified, for instance cel- 60 lulose nitrate or amyl acetate might be employed in place of the cellulose acetate, although the latter is preferable by reason of its relative non-combustible character, and other softening agents than dichlorhydrin 65 might be employed. Upon the evaporation of the solvents, a hard solid film or plate will remain which may be readily removed from the painting without in any way injuring the latter. Under ordinary conditions 70 48 hours is sufficient to effect the complete and desired evaporation, although this time might be shortened by a slight increase in temperature or a reduction in pressure. The time will vary with the thickness of the 75 layer of solution on the painting. This film or plate will conform, on its under surface, to the surface of the painting and will be flat on its upper surface. When the solvent has evaporated the residue will be suffi- 80 ciently hard to itself constitute the die. My improved process can be carried out in this way only when the colored print is a full-sized reproduction of the original painting, and when the original painting is available 85 for the making of the matrix or die.

I may carry out my improved process by making or securing a colored print as above described which may be either larger, smaller or the same size as the original 90 painting. The print may be traced on to a piece of canvas or photographically reproduced thereon, and an artist then may paint on the canvas so as to produce the brush marks, varying thicknesses of paint, and 95 other surface irregularities corresponding with those of the original painting or closely approximating the same. This painting on the canvas need not be in the colors of the original painting and in fact it may be done 100 in ordinary white paint, it only being es- sential that the proper amount of paint be applied to the canvas in the proper places and the proper brush marks produced. When the paint is dry a die or matrix is 105 made from it as above described. It is evi- dent that this matrix will correspond in size with the colored print irrespective of whether the latter be larger or smaller than the original painting from which the print 110 was made.

The colored print and the die or matrix

are now superposed and sufficiently high pressure is brought to bear to emboss the print by the die. Preferably the print is previously pasted on a piece of canvas or it may be caused to adhere to the canvas by the pressure applied in embossing the print.

The degree of pressure required will of course depend upon the character of the paper or other material upon which the colored print is made and the extent of the irregularities in the contour of the face of the die or matrix. In bringing the die and print together it is of course evident that care should be exercised in getting the two in perfect registry so that the embossing and printing will bear the proper relationship and correspond exactly to the original painting.

The completed article will thus have a backing of actual canvas and the front surface will be an exact reproduction of the original painting not only as regards color, shading and lines, but also as regards the surface irregularities.

I have described my improved process as being one for securing exact reproductions of oil paintings, on canvas, but it is of course evident that the process may be employed for securing exact reproductions of other surfaces which vary in color or shading and vary slightly in contour.

Having thus described my invention, what I claim is:

1. The process of reproducing pictures which consists in producing on an embossable surface a photographic reproduction of the picture in its true and natural colors, applying a solution of a solid substance in a vaporizable solvent to the face of the picture, evaporating the solvent to leave a hard matrix, the face of which corresponds to the surface irregularities of the original picture, and using said matrix itself as a die to emboss the colored photographic reproduction.

2. The process of reproducing pictures which consists in producing on an embossable surface a photographic reproduction of the picture, applying a solution of a solid substance in a vaporizable solvent to the face of the picture, evaporating the solvent to leave a matrix, the face of which corresponds to the surface irregularities of the original picture, and using said matrix as a die to emboss the photographic reproduction.

3. The process of reproducing pictures which consists in producing on an embossable surface a photographic reproduction of the picture, applying a solution of cellulose

acetate in tetrachlorethane and dichlorhydrin to the face of the picture, evaporating the solvent to leave a matrix, the face of which corresponds to the surface irregularities of the original picture, and using said matrix as a die to emboss the photographic reproduction.

4. The process of reproducing pictures which consists in producing a colored photographic print of a painting and on an embossable surface, applying paint to a sheet of canvas to simulate the brush marks and the varying thicknesses of paint of the original painting, forming a die by applying a composition to the painted face of said canvas and causing said composition to acquire a hard, solid form with one surface corresponding to the surface irregularities of the painted canvas, mounting said colored photographic reproduction on a second sheet of canvas and embossing said colored reproduction by pressing it on to said second sheet of canvas with said die.

5. The process of reproducing pictures which consists in applying paint to a sheet of canvas to simulate the brush marks and the varying thickness of paint of the original painting, forming a die by applying a composition to the painted face of said canvas and causing said composition to acquire a hard, solid form with one face conforming to the surface irregularities of the painted canvas and removing the die from the painted canvas and pressing it on a colored photographic print of the painting.

6. The process of reproducing pictures which consists in applying paint to a sheet of canvas to simulate the brush marks and the varying thickness of paint of the original painting, forming a die by applying to the painted face of the canvas a composition including a solid substance dissolved in a vaporizable solvent, evaporating the solvent to leave the solid substance as a hard film or sheet, the under surface of which corresponds to the surface irregularities of the painted canvas, removing said film or sheet, and pressing the latter upon a colored photographic reproduction of the original painting.

Signed at New York city in the county of New York and State of New York this 28th day of November, A. D. 1913.

HENRY PETERS.
